(57) **CLAIM**

What is claimed is the ornamental design for a “breakaway connector for medical lines”, as shown and described.

DESCRIPTION

FIG. 1 is a left end perspective view of the “breakaway connector for medical lines” of Applicant’s invention.

FIG. 2 is right end perspective view of the “breakaway connector for medical lines” of Applicant’s invention.

FIG. 3 is front view of the “breakaway connector for medical lines” of Applicant’s invention.

FIG. 4 is a back view of the “breakaway connector for medical lines” of Applicant’s invention.

FIG. 5 is a top view of the “breakaway connector for medical lines” of Applicant’s invention.

FIG. 6 is a bottom view of the “breakaway connector for medical lines” of Applicant’s invention.

FIG. 7 is a left end view of the “breakaway connector for medical lines” of Applicant’s invention; and,

FIG. 8 is a right end view of the “breakaway connector for medical lines” of Applicant’s invention.

In the Figures, the dashed lines represent portions of the surroundings and do not form part of the claimed invention.
